WARNING SIGNAL

Alexis F. Gillet, Omaha, Nebr., assignor to Jubilee Manufacturing Co., Omaha, Nebr., a corporation of Nebraska

Application January 20, 1934, Serial No. 707,607

4 Claims. (Cl. 116—142)

This invention relates to sounding devices and more particularly to a device adapted to generate warning sounds for use in conjunction with automobile or vehicle engines.

5 It is an object of the invention to provide an arrangement of parts operated by vacuum created by the suction strokes of the pistons of an internal combustion engine, said arrangement to be efficiently operable at times when the pistons are reciprocating at high speed.

10 Another object of the invention is to provide a resilient spider bearing arranged to maintain all portions of the perimeter of a valve employed equidistant with respect to an air intake aperture of the horn for providing a device of better tonal qualities and assuring that warning signals will sound efficiently at high motor speeds and at times when the rings of the pistons thereof are loose or unduly worn.

15 Other and further objects and advantages of the invention will be understood from the following detailed description reference being had to the accompanying drawing, in which:

20 Figure 1 is a vertical cross section through a horn embodying the present invention, certain portions of the bell of the horn being broken away.

25 Figure 2 is a sectional view taken substantially on the line 2—2 of Figure 1.

30 Figure 3 illustrates the alignment of a valve with respect to a transversely disposed wall employed at the time the valve is open.

35 Figure 4 is a bottom plan view of a resilient spider member associated with the valve.

40 It will be understood that the term spider bearing as herein used means a bearing having a plurality of points of suspension but not less than three thereof.

45 In the drawing the numeral 10 indicates generally a sounding device which includes a housing comprised of a lower half portion 11 and an upper half portion 12.

50 The lower part 11 of the housing is substantially cup-shaped in cross section having an out-turned flange 13 and an inturned flange 14. A nut 15 is provided with an annular recess within which the flange 14 is received for attaching the parts together during manufacture, thereby providing an economical construction. The nut facilitates the communication of the horn with the intake manifold of an internal combustion engine, it being understood that a suitable cut-off cock, not shown, is provided for use at times when it is desired to employ the device for the production of intermittent warning signals. Between the

flanges 13 and 14 a detent-shelf 16 is provided for purposes later explained.

The upper half portion 12 of the housing includes a flange 17 which is peened over the flange 13 of the lower half portion during the manufacture of the device and subsequent to the placement of certain later described parts therein.

5 A bell 18 may be employed for amplifying sounds produced by the device and is in communication with the interior of the housing 10 through an opening 19 formed through the upper half portion 12 of the housing. The bell 18 may be removably secured to the horn by means of a boss 20 and keepers 21.

The nut 15 is provided with a threaded outlet 15 port 22 for a communication with a source of suction. Prior to the peening of the half portions of the housing together a transversely disposed wall 23, a valve 24 and a resilient spider member 25 are placed within the housing and arranged 20 as shown in Figure 1.

25 Figure 1 is a vertical cross section through a horn embodying the present invention, certain portions of the bell of the horn being broken away.

30 Figure 2 is a sectional view taken substantially on the line 2—2 of Figure 1.

35 Figure 3 illustrates the alignment of a valve with respect to a transversely disposed wall employed at the time the valve is open.

40 Figure 4 is a bottom plan view of a resilient spider member associated with the valve.

45 It will be understood that the term spider bearing as herein used means a bearing having a plurality of points of suspension but not less than three thereof.

50 In the drawing the numeral 10 indicates generally a sounding device which includes a housing comprised of a lower half portion 11 and an upper half portion 12.

55 The lower part 11 of the housing is substantially cup-shaped in cross section having an out-turned flange 13 and an inturned flange 14. A nut 15 is provided with an annular recess within which the flange 14 is received for attaching the parts together during manufacture, thereby providing an economical construction. The nut facilitates the communication of the horn with the intake manifold of an internal combustion engine, it being understood that a suitable cut-off cock, not shown, is provided for use at times when it is desired to employ the device for the production of intermittent warning signals. Between the

flanges 13 and 14 a detent-shelf 16 is provided for purposes later explained.

55 The upper half portion 12 of the housing includes a flange 17 which is peened over the flange 13 of the lower half portion during the manufacture of the device and subsequent to the placement of certain later described parts therein.

55 A bell 18 may be employed for amplifying sounds produced by the device and is in communication with the interior of the housing 10 through an opening 19 formed through the upper half portion 12 of the housing. The bell 18 may be removably secured to the horn by means of a boss 20 and keepers 21.

The normal position of the parts is as shown in Figure 1, the central portion of the spider member being slightly bowed away from the wall 23 and it will be understood that the closure member 24 reciprocates during a sounding of the device incident to suction applied to the chamber 29 and when the valve 24 moves away from the wall 23, as shown in Figure 3, the bearing maintains the alignment of the closure member 24 constant with respect to the wall 23, as shown in Figure 3, for causing air entering the chamber to be distributed in an equal volume about all portions of the closure member. Also it will be understood that when the valve 24 flutters or reciprocates incident to the production of warning signals an equal volume of air contacts with all portions of the edge of the wall 23 adjacent to the aperture 28 due to the flat surface 34 of the valve 24 being maintained in alignment with the flat surface 35 of the wall 23 by the said bearing.

As heretofore practiced in the art helical springs have been employed for valve members riding in bearings and valves have been suspended with a plurality of coiled springs. In the first mentioned prior construction the bearing upon becoming worn permits the valve to tilt with respect to its seat and in the latter the springs necessarily being of unequal tension permit the same, whereby both said prior constructions are not conducive to the best results when used in conjunction with vacuum operated warning signals.

It is believed to be obvious that since the resilient arms 33 of the present invention are integral and punched from a unitary piece of sheet metal in the manufacture of the device that each arm provides an equal pressure with respect to its mates and also on account of the detent shelf 16 being punch pressed in an accurate die during the manufacture of the lower half portion 11 of the housing, the said shelf is accurately formed with all portions thereof equidistant from the wall 23, and as thus described it will be understood that no adjustments are required subsequent to assembling the parts of the device permanently within the housing.

Having thus described my invention, what I claim as new and desire to secure by Letters Patent is:—

1. A sounding device comprising a housing arranged to provide a chamber having an outlet port for a communication with a source of suction, said chamber having a wall provided with an air intake aperture, a detent-shelf within the housing, a reciprocable closure-member for the aperture having a surface disposed in par-

allelism with said wall, and a member provided with not less than three similar integral radially disposed resilient arms carrying the closure-member for maintaining the latter in an initial yieldable position normally sealing the aperture, the outer ends of said arms being substantially equi-distant with respect to each other and resting upon the shelf for providing a spider bearing, whereby when the closure member reciprocates during a sounding of the device incident to suction applied to the chamber the spider bearing maintains the said parallelism of the closure-member constant with respect to the wall. 5 10 15

2. A device of the character described comprising a housing arranged to provide a chamber adapted to have a communication with a source of suction and provided with a wall, said wall having a flat surface provided with a centrally disposed aperture for the entrance of air 20 into the chamber, a reciprocable valve having a flat surface normally disposed against the flat surface of the wall, and a resilient member having not less than three similar radially disposed yieldable arms for providing a spider bearing, 25 means for securing said member to the valve for yieldably causing the latter to normally seal the aperture, said spider bearing arranged to maintain all portions of the perimeter of the valve equi-distant with respect to the aperture during 30 a sounding of the device.

3. A device of the character described comprising a housing arranged to provide a chamber having an air intake aperture and an outlet port adapted to have a communication with 35 a source of suction, a reciprocable closure member within the housing for normally sealing the aperture, and a resilient spider secured to the closure member for maintaining all portions of the perimeter of the latter equi-distant with respect to the aperture during a sounding of the device, said spider supporting said closure member constantly parallel to said aperture. 40

4. A device of the character described comprising a housing having a chamber arranged 45 for a communication with a source of suction, said chamber having a wall provided with a central aperture for a communication with the atmosphere, a reciprocable closure member for normally sealing the aperture, and a resilient spider secured to the closure member for urging the closure member toward the aperture, and supporting said closure member in a position to close said aperture and constantly parallel thereto. 50
